UNITED STATES PATENT OFFICE.

ARTHUR RAYNSFORD, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,386,730.

Specification of Letters Patent.

Patented Aug. 9, 1921.

Application filed December 31, 1919. Serial No. 348,511.

To all whom it may concern:

Be it known that I, ARTHUR RAYNSFORD, a citizen of the United States, residing at New York, in the county of New York, 5 State of New York, have invented certain new and useful Improvements in Telephone-Exchange Systems, of which the following is a full, clear, concise, and exact description.

10 This invention relates to telephone exchange systems and more particularly to such systems involving an automatic exchange and a toll exchange. More specifically the invention relates to means for indicating to an operator at a toll exchange the class of service to which a subscriber, whose line has been extended to her position is entitled. For example, some stations of an automatic exchange may be entitled to toll 15 connections, while others may not.

20 The object of the invention is to provide in a system of this nature, means for automatically indicating to an operator whether a calling line, which has been extended to her position, is entitled to toll connections or not.

25 A feature of the invention consists in the provision of means for inductively transmitting a tone, over two conductors of a 30 trunk circuit extending between two exchanges, to an operator's telephone set connected to the trunk, with means under the control of the operator for disconnecting the tone from her set and reconnecting it at will.

35 In the drawings, Figures 1 and 2 placed side by side represent the circuit arrangements of one embodiment of the invention, only so much being shown of the circuits and 40 apparatus as is necessary for a clear understanding of the present invention. The circuits and apparatus shown in Fig. 1 are located at the automatic exchange while those shown in Fig. 2 are located at the toll or manual exchange.

45 A calling subscriber, of the automatic exchange whose station is indicated at A, extends his line to an operator's position at the toll or manual exchange shown in Fig. 50 2 by operating switches under the control of sender S. The line finder B and selector switch C schematically represented may be of the type disclosed in the Patent No. 1,334,300, to Charles L. Goodrum, issued

March 23, 1920, in which case induction coil 55 5, generator 4 and the connections therefor of the present drawing would take the place of the coil 135, generator 136 and the connections therefor shown in that patent. Lines not entitled to special service or to 60 toll connections would be provided with a connection to the source of tone supply. That part of the apparatus of the trunk circuit extending between the automatic and toll exchange located at the automatic exchange is indicated in Fig. 1 as D while that part located at the manual or toll exchange is indicated in Fig. 2 as E. The trunk circuit terminates at the manual exchange in a jack 111. A cord circuit F located at the operator's position is shown in Fig. 2, to which an operator's telephone set is normally connected. The operation of the system is such that as soon as the operator plugs into the jack of a trunk over which 75 a call has arrived, the tone is heard in the set of the operator if the line is not entitled to toll connections. Terminating at the operator's position in jack 126 and extending to a chief operator's or supervisor's desk, 80 is a trunk circuit G, by means of which the operator may extend the line of a calling subscriber to the chief operator in case any dispute arises as to the right of the calling station to have a toll connection. A cord 85 circuit H is provided at the desk by means of which the desk operator may converse with the calling subscriber.

With this description of the elements it is thought the invention will be more fully 90 understood by reference to the following detailed description of the operation.

A subscriber at substation A desiring a toll connection removes the receiver from the switchhook and operates the sender S to select an idle trunk leading to the toll exchange in the manner described in the above mentioned patent.

When the calling substation A is extended to the idle trunk leading to the toll 100 exchange, relay 10 of the trunk circuit D is energized over a path extending from grounded battery through the left-hand winding of relay 10, terminal 29, brush 26, brush 23, terminal 20, through the substation loop, terminal 21, brush 24, brush 27, terminal 30, and right-hand winding of relay 10 to ground. Relay 10 in operating

completes a circuit at its front contact and left-hand armature for slow-to-release relay 11. Relay 11 in attracting its armatures removes ground from terminal 31 of the trunk 5 circuit thereby rendering the trunk busy and completes a circuit for slow-to-release relay 12. The latter circuit may be traced through ground, front contact and inner right-hand armature of relay 11, and winding of relay 12 to grounded battery. Relays 10 and 12 in operating complete a circuit through relay 13 in that portion of the trunk circuit D at the automatic exchange and for relay 101 in that portion of the trunk circuit 10 at the toll exchange. This circuit may be traced as follows: grounded battery, front contact and armature of relay 12, right-hand winding of relay 13, upper left-hand winding of repeating coil 102, through the left-hand and right-hand windings of relay 101 15 in series, lower left-hand winding of repeating coil 102, right-hand armature and front contact of relay 10 and left-hand winding of relay 13 to ground. Relay 13 is marginal and will not operate in series with the right-hand winding of relay 101 due to the high resistance of such winding. Relay 101 in operating completes a parallel circuit for ringing relay 104, and line signal 105 which 20 may be traced from ground, armature and front contact of relay 101, left-hand normal contacts of relay 106, and thence through the winding of relay 104 and line signal 105 in parallel, to grounded battery. Relay 104 in energizing connects a source of 25 ringing tone to the trunk which serves as a signal to the calling subscriber that the toll operator is being signaled and signal 105 in lighting indicates to the operator that 30 a call has arrived over the trunk with which it is associated.

The operator at the toll exchange observing the line signal inserts plug 110 into jack 111 whereupon a circuit is completed for relays 113 and 112 in series, said circuit extending from ground, winding of relay 113, sleeves of jack 111 and plug 110, through the winding of relay 112 to grounded battery. Relay 113, in operating, at its front contact 45 and inner left-hand armature, shunts the right-hand, high resistance winding of relay 101 which permits the marginal relay 13 associated with the trunk circuit at the automatic exchange to operate in series with the low resistance, left-hand winding of relay 101. Relay 113 in operating also completes a circuit for relay 106 which circuit extends from grounded battery, through winding of relay 106, right-hand armature 50 and front contact of relay 113 and right-hand armature and back contact of relay 106 to ground. Relay 106 in operating locks up under control of relay 101, and opens the circuit for relay 104 and line signal 105. A 55 circuit for relay 120 is prepared and it will

operate in series with relay 106 as soon as the direct path to ground through the front contact and armature of relay 101 is opened. When relay 13 at the automatic exchange is operated, a circuit is completed at its 70 right-hand armature and front contact for relay 15. Relay 15 in operating completes a circuit at its outer armature and front contact for relay 17 thereby inductively connecting the source of tone supply to the operator's telephone set, and at its inner armature and front contact, for relay 14, which locks up under the control of relay 11. The circuit for the energization of relay 17 may be traced as follows: ground, outer right-hand armature and front contact of relay 15, outer left-hand armature and back contact of relay 16, winding of relay 17, and left-hand armature and front contact of relay 10 to grounded battery. The path for 75 the tone may be traced as follows: grounded battery, secondary winding of induction coil 5, winding of cutoff relay 6, terminal 22, brush 25, brush 28, terminal 31, left-hand armature and front contact of relay 11, 80 left-hand armature and front contact of relay 17, condenser 18, and primary winding of induction coil 19 to ground. The interrupter 4, by means of the primary winding of the coil 5 induces an alternating current 85 in the secondary and over the circuit just traced. The primary winding of coil 19 induces a current in the secondary winding of this coil which is in a circuit which may be traced as follows: secondary winding of 90 coil 19, right-hand armature and front contact of relay 17, lower left-hand winding of repeating coil 102, condenser 160, upper left-hand winding of repeating coil 102, condenser 40 to the secondary winding of coil 95 100 19. From the left-hand winding of repeating coil 102, the alternating current is induced in the right-hand winding and thence transmitted over a circuit to the operator's telephone set (not shown). This circuit includes the secondary winding of repeating coil 102, upper and lower normal contacts of relay 120, tip and ring of jack 111 and plug 110 and the normally closed contacts of listening key 121. 110 The operator thus hears the tone as soon as plug 110 is inserted into the jack 111 and will inform the subscriber that toll connections from his station are not permitted. 115 After having heard the tone the operator 120 may, in order to better converse with the calling subscriber, actuate key 107 which results in the disconnection of the tone from the operator's position. Actuation of key 107 establishes a circuit for relay 103, which 125 in operating opens the shunt around the high resistance winding of relay 101. Relay 13 releases, when the high resistance winding of relay 101 is connected in series with it, and in retracting its armatures 130

attracting its armature completes a circuit for supervisory lamp 141 said circuit including the lower contact of key 121 which is in its operated position, said key having been 5 actuated by the operator in referring the call to the desk. When the desk operator removes the plug 132 from jack 131 the circuit for relay 130 is opened and lamp 137 is extinguished which indicates to the operator that the desk operator has disconnected. The operator removes the plugs 10 from their associated jacks upon receiving the disconnect signals whereupon all relays at the toll exchange are released. Relay 113 upon deenergization opens the circuit for relay 13 at the automatic exchange. The latter in releasing its armatures restores all 15 relays in the trunk circuits at the automatic exchange to normal and the system is ready 20 for the next call.

What is claimed is:

1. In a telephone system, an office, telephone lines of different classes terminating therein, a second office, trunks interconnecting 25 said offices and having two wires only, an operator's position at said second office wherein said trunks terminate, a cord circuit thereat, automatic switches at said first office adapted to be set under the control of 30 the calling subscriber to seize one of said trunks, and means for immediately automatically indicating the class of the calling line to the operator at the second office as soon as said cord circuit is connected to a 35 seized trunk.

2. In a telephone system, an office, telephone lines of different classes terminating therein, a second office, trunks interconnecting 40 said offices and having two wires only, an operator's position at said second office wherein said trunks terminate, a cord circuit thereat, an operator's telephone set therefor, automatic switches at said first office, set under control of a calling line to seize one 45 of said trunks, a tone source associated with certain of said lines automatically connected to said operator's telephone set as soon as the cord circuit is connected to said trunk for indicating to the operator the class of 50 the calling line, and means controlled by the operator for removing the tone and for again causing the tone to be impressed upon the trunk at will.

3. In a telephone system, an office, telephone lines of different classes terminating 55 therein, a second office, trunks interconnecting said offices, an operator's position at said second office wherein said trunks terminate, automatic switches at said first office set 60 under the control of the calling party to seize one of said trunks, a cord circuit at said operator's position for seizing said trunk, a tone source automatically connected to said trunk as soon as said trunk is seized 65 by the operator to indicate to the operator

the class of the calling line, means controlled by the operator for removing the tone, a second operator's position, and means controlled by the operator at the first position for extending the trunk to the second position and for again causing the tone to be impressed on the trunk. 70

4. In a telephone exchange system, an automatic exchange, a calling line thereat, a source of tone supply associated with said line, a manual exchange, a two-conductor trunk circuit extending between said exchanges terminating in a jack at said manual exchange, a cord circuit at said manual exchange, an operator's telephone set connected 75 thereto, means including automatic switches for extending said calling line to said jack, means responsive to the connection of said cord circuit with the jack of said trunk circuit for inductively connecting said source of tone supply to said operator's telephone set, and operator-controlled means for disconnecting said source of tone supply from 80 said operator's telephone set. 85

5. In a telephone exchange system, an automatic exchange, a manual exchange, a calling line at said automatic exchange, a tone generator associated with said calling line, an operator's position at said manual exchange, means including a two conductor 90 trunk circuit for extending said calling line to said operator's position, a relay at said automatic exchange adapted upon energization to inductively connect said tone generator to said operator's position, and operator-controlled means for energizing said 95 relay. 100

6. In a telephone exchange system, an automatic exchange, a manual exchange, a calling line at said automatic exchange, a source of tone supply associated with said calling line, an operator's position at said manual exchange, means including a two conductor trunk circuit for automatically extending 105 said calling line to said operator's position, a relay at said automatic exchange adapted upon energization to inductively connect said source of tone supply to said operator's position, and operator-controlled means for energizing and deenergizing said 110 relay. 115

7. In a telephone exchange system, an automatic exchange, a manual exchange, a two conductor trunk circuit extending between said exchanges, a jack at a switchboard in 120 which said trunk circuit terminates at said manual exchange, a calling line at said automatic exchange, a tone generator associated with said calling line, means including automatic switches for extending said calling line to said jack, a cord circuit at said switchboard, an operator's telephone set connected to said cord circuit, a relay associated with the trunk circuit at said automatic exchange adapted upon energization 125 130

to inductively connect the tone generator to the jack at said switchboard, and means responsive to the connection of said cord circuit with said jack for inductively connecting said tone generator to said operator's telephone set.

8. In a telephone exchange system, an automatic exchange, a manual exchange, a two-conductor trunk circuit extending between said exchanges, a calling line, automatic switches operable by the subscriber of said calling line for extending said line to the manual exchange, a tone generator, a relay associated with the trunk circuit at the automatic exchange adapted upon energization to inductively connect the tone generator to the talking conductors of said trunk circuit, means responsive to the connection of said cord circuit, with said trunk circuit for energizing said relay, a key associated with said trunk circuit, and means responsive to the actuation of said key for deenergizing said relay.

9. In a telephone exchange system, an automatic exchange, a calling line thereat, a source of tone supply associated with said line, a manual exchange, an operator's position at said manual exchange, a two-conductor trunk circuit extending between said exchanges, means including automatic switches for extending said calling line over said trunk circuit to said operator's position, a cord circuit at said operator's position having an operator's telephone set connected thereto, means responsive to the connection of said cord circuit with said trunk circuit for inductively connecting said tone generator to said telephone set, operator controlled means for disconnecting said tone generator from said telephone set, a supervisory signal associated with said cord circuit, and means controlled by the subscriber of the calling line for actuating said signal.

In witness whereof, I hereunto subscribe my name this 30th day of December A. D., 1919.

ARTHUR RAYNSFORD.
